UNITED STATES PATENT OFFICE.

MARTIN W. LONGFELLOW, OF BALTIMORE, MARYLAND, ASSIGNOR TO THE BALTIMORE GAS APPLIANCE AND MANUFACTURING COMPANY, OF BALTIMORE, MARYLAND, A CORPORATION OF MARYLAND.

TOP FOR GAS-RANGES.

1,170,766.

Specification of Letters Patent.

Patented Feb. 8, 1916.

Application filed January 12, 1914. Serial No. 811,574.

To all whom it may concern:

Be it known that I, MARTIN W. LONGFELLOW, a citizen of the United States, residing at Baltimore, in the State of Maryland, have invented new and useful Improvements in Tops for Gas-Ranges, of which the following is a specification.

This invention relates to an improved top for gas ranges.

10 In gas stoves and ranges as now constructed, the top which supports the articles to be heated above the gas flame, is usually constructed in the form of a grid or grill. This construction is open to objection for 15 the reason that the overflow from the cooking passes through to the pan which is usually located below the burners. Furthermore the open top of this type is open to objection because there is no surface which 20 is warm enough to keep cooked articles from cooling rapidly.

One of the objects of the present invention is to provide a top for gas stoves and the like, which may be readily cleaned and so 25 constructed as to prevent a large portion of the overflow from the cooking from running through to the pan which is located below the burners.

A further object is to provide a top which 30 will permit the shifting of the cooking vessel to a surface which will be more or less warm, due to conductivity.

A further object is to provide a top so 35 constructed that air currents are prevented from interfering with the direct contact of the flame or heat with a vessel supported by said top, whereby concentration of the heat is effected.

A further object is to provide a top having 40 openings arranged above the burners, but otherwise imperforate, and having means for providing heat channels which will permit of the passage of heat from the burner under the vessel.

45 A further object is to provide a series of said heat channels radiating from the burners and occupying the space between the burners.

A further object is to provide a plurality 50 of channels for conducting the over-flow, from the cooking in such manner as to protect the burners.

The invention will be hereinafter fully set forth and particularly pointed out in the claims.

55 In the accompanying drawings:—Figure 1 is a top plan view illustrating a simple type of gas stove with my invention applied thereto. Fig. 2 is a longitudinal sectional view of the top plate and Fig. 3 is a transverse sectional view thereof. Fig. 4 is a view of the top removed. Fig. 5 is a plan view of a slight modification.

60 Referring to the drawing, 10 designates a gas stove body supported by legs or standards 11 and provided with the burners 12, the latter being connected with a suitable supply pipe 13, said burners and supply pipe being supported by arms or brackets 14. It will be understood that while I have 65 shown and described this simple form of gas stove for illustrative purposes, my present invention is not limited thereto but is applicable to all forms of gas stoves, nor 70 is it limited to the particular type of burner 75 illustrated.

75 Secured to the body 10, and located above the burners 12 is the top plate 15. This plate is formed of a single piece of metal provided with openings 16 immediately 80 above the outlet portions of the burners, but otherwise imperforate. It will be observed that the said plate is provided with an undulating surface formed by alternating ridges 17 and depressions 18 surrounding the respective openings 16, and radiating therefrom. The body of the plate is cut away to form radiating recesses 19 in the depressed portions 18 and between the ridges 17, to conform to the shaft of the 85 burners. If desired a simmer burner may be employed, in which event the plate is provided with an opening 20 above said burner, said opening being surrounded by alternating ridges and depressions 21, 22 respectively.

90 From the foregoing it will be seen that my improved top is open only at points immediately above or opposite the flame of each burner, and that between the flames 100 there is a ridge and a depression both of which serve to permit the escape of the products of combustion. The depressions serve to catch and retain a large percent-

age of the overflow from the cooking, and the arrangement is such that the top may be readily and easily cleaned. Said depressions also serve as channels. Furthermore 5 the top as an entirety is heated to a greater or less extent by the gas flames so that cooking vessels may be shifted from points over the flames, and yet be kept warm due to the heat retained by the plate through conductivity.

The openings 16 permit the passage of the gas flames, heat and products of combustion, and the undulations in the top are so placed that the air currents do not interfere 15 with the direct contact of the flame or heat with a cooking vessel, thus effecting a concentration and conserving of the heat.

In Fig. 5 I have shown a slight modification in which the top 15 is provided with 20 circular openings in which are inserted ring-grates 22 provided with raised ribs 23 arranged in prolongation of the ridges 17.

Having thus explained the nature of my invention and described an operative manner of constructing and using the same, although without attempting to set forth all of the forms in which it may be made, or all of the forms of its use, what I claim is:—

1. A top for gas ranges and the like comprising a plate formed of a single piece of metal having openings adapted to register with gas burners, said plate having an undulating top surface between and around all of said openings, the depressed portions of said 35 surface forming draining channels for the areas between said openings, and adapted to coöperate with a vessel upon said plate to form flues leading from the burners.

2. A top for gas ranges and the like comprising a plate provided with openings 40 adapted to register with gas burners, the top surface of said plate having undulations radiating from and surrounding the respective openings, the depressed portions of said 45 surfaces forming draining channels for the areas between said openings and adapted to

coöperate with a vessel upon said plate to form flues leading from the burners.

3. A top for gas ranges and the like comprising a plate formed of a single piece of 50 metal provided with spaced apart openings adapted to register with the gas burners, and having alternating ridges and depressions between and around the respective openings, the depressions forming draining channels 55 for the areas between said openings, and adapted to coöperate with a vessel upon said plate to form flues leading from the burners.

4. A top for gas ranges and the like comprising a plate formed of a single piece of 60 metal having openings adapted to register with gas burners, said top plate having an undulating surface between and around the 65 respective openings, the depressed portions of said surface forming draining channels for the areas between said openings, and adapted to coöperate with a vessel upon said plate to form flues leading from the burners, the depressed portions being provided with radiating recesses arranged around said 70 openings.

5. A top for gas ranges and the like comprising a plate formed of a single piece of metal provided with spaced apart openings adapted to register with the gas burners and 75 having alternating ridges and depressions between and around the respective openings, the depressions forming draining channels for the areas between said openings, and adapted to coöperate with a vessel upon said 80 plate to form flues leading from the burners, in combination with ring grates located in said openings and provided with raised ribs in prolongation of said ridges.

In testimony whereof I have hereunto set 85 my hand in presence of two subscribing witnesses.

MARTIN W. LONGFELLOW.
